METHOD AND APPARATUS FOR MAKING
LACE FABRIC

Arnold Friedrich Verbeek, Oberlungwitz, Germany, assignor to Karl Lieberknecht G. m. b. H., Oberlungwitz, Germany, a corporation of Germany

Application July 30, 1932, Serial No. 626,860,
and in Germany August 12, 1931

6 Claims. (Cl. 66—96)

This invention relates to method and apparatus for making lace fabric, and more particularly to improvements in the construction and operation of flat knitting machines to adapt them for this purpose.

In the manufacture of mesh lace or net full fashioned stockings on a flat knitting machine, it has been customary to form an opening in the fabric at desired points, by transferring a loop 10 outwardly from a knitting machine needle to an adjacent needle and transferring an adjacent loop outwardly in the opposite direction to an adjacent needle. When the next course is laid, the new thread adjacent to the empty needles is 15 left loose, and lies behind these empty needles. To close the opening, this loose thread is transferred to one of the adjacent loop-carrying needles, and this loose thread must also be brought in front of one of the empty needles, so that the 20 loops of the next course may intermesh therewith.

Heretofore this loose thread has been brought in front of one of the empty needles, by giving the 25 needle bar a special rearward movement after the delivery of the transferred thread to the adjacent needle. Certain of the needles, which were in engagement with the transfer points used for the transfer operation, were held back thereby, which by bending or springing these needles, 30 threw them out of line with the remaining needles. Hence when the needle bar moved upward, the empty needle adjacent to the needle to which the loose thread had been transferred, came up behind the thread, which was held taut in a sloping 35 position, extending from the other of the originally empty needles to the needle held by the transfer point.

This expedient caused a severe strain upon the 40 needles, and was unreliable, because a slight deflection of the transfer points prevented the special movement of the needle bar from causing a sufficient difference in position of the respective needles to bring the thread in front of one but behind the other of the empty needles.

45 It is therefore an object of the present invention to provide method and apparatus of this character which avoids the difficulty referred to above, and which is certain in operation.

Another object of the invention is to make 50 lace fabric on a flat knitting machine without requiring a special movement of the knitting needle bar.

Further objects are to simplify and improve 55 the construction and operation of mechanism for adapting flat knitting machines for making

lace fabric, and to render the same otherwise well adapted for the purposes set forth.

Other objects and features of novelty will be apparent as the following description proceeds, reference being had to the accompanying drawing, in which—

Figure 1 is a diagram showing two normal courses, the four loops of the last course being respectively carried by four knitting needles, the arrows showing the directions in which the loops 65 are to be transferred;

Figure 2 is a similar view, showing the loops after transfer;

Figure 3 shows the next course laid, with the thread lying loose behind the empty needles;

Figure 4 shows the new step for bringing the loose thread in front of one of the empty needles, by means of an auxiliary needle, without special movement of the knitting needle bar, or excessive bending of the needles;

Figure 5 shows the next course laid in the usual manner;

Figure 6 is a side elevation of the novel arrangement including the new auxiliary needle as mounted in the knitting machine;

Figure 7 is a front elevation of the structure shown in Figure 6;

Figure 8 is a view similar to Figure 6, but showing a preferred modification of the auxiliary needle;

Figure 9 is a front elevation of the same; and

Figure 10 is a side view of the structure shown in Figure 9.

Figures 1 to 5 inclusive show the new method of forming the opening for the mesh lace. In 90 these views the loops are carried by knitting needles 1, 2, 3 and 4. The loose thread of the subsequent course adjacent the empty needles 2 and 3 is shown at 5 in Figures 3, 4 and 5.

The parts of the knitting machine which are 95 pertinent to the invention are shown in Figures 6 and 7 as comprising a transfer point 6 and the new auxiliary needle 7, which operate between knocking over bits 8 and are carried by a transfer bar or lace bar 9. The construction 100 and operation of bars like the bar 9 are well known in the art, in machines having lace bars. An example of such a machine is shown in the patent to Albert Gee, No. 703,055, granted June 4th, 1902.

To form the opening for the lace mesh, the loops on needles 2 and 3 as shown in Figure 1, are transferred outwardly in the direction of the arrows, to needles 1 and 4, as shown in Figure 2. For this purpose, a transfer point such as 6 is 110

moved down over the needle 2. The transfer point is grooved to fit over the needle, and press the beard inwardly, so that as the needle and transfer point move down together, the loop is not caught by the beard, but slides onto the transfer point. The transfer point then moves laterally and descends over the needle 1. Then the transfer point rises, leaving the loop from the needles 2 now on the needle 1, so that this 10 needle now carries both loops, and needle 2 is empty. A similar transfer operation in the opposite direction transfers the loop from needle 3 to needle 4 which carries both loops, leaving needle 3 empty.

15 When the next course is laid, as shown in Figure 3, needles 1 and 4 form normal loops, but as the needles 2 and 3 are empty, they cannot form loops, and hence the thread 5 adjacent these needles lies loose on the knocking over 20 bits 8 behind the needles 2 and 3. This thread 5, in order to close the opening, must be brought in front of one of the empty needles, such as the needle 3.

Heretofore to accomplish this according to a 25 prior method, the thread 5 was transferred to an adjacent needle such as the needle 4, by a transfer point 6. Then the needle bar was given a special additional rearward movement, which moved the needles 1, 2 and 3, but not the needle 30 4 which was held forward by the transfer point 6. At this time in the operation of the machine, the loop portion of the thread 5 which was on the transfer point 6, was above the portion which was on the needle 2, because the transfer point 35 6 had moved upward with this portion of the thread 5 thereon. Hence the thread 5 extended tautly from the needle 2, sloping upward to the transfer point 6. The difference in height as 40 well as alignment of the needle 2 and the transfer point 6 served to bring the central portion of this thread 5 in front of the needle 3. Then, when the needle bar moved upward, the needle 45 3 came up behind the thread 5. The needle bar was then returned from its special additional rearward movement, and the next course was 50 laid in the usual manner as shown in Figure 5, because the thread of this next course was now able to intermesh with the thread 5 so as to form the loops over needles 2 and 3.

55 In the former step as described above, the expedient for getting the thread 5 in front of the needle 3 was not found to be satisfactory in practice. The relative displacement of the needles 3 and 4 subjected the needles to repeated excessive bending stresses, which was undesirable in this delicate mechanism. Furthermore, a slight deflection of the transfer point 6 defeated the entire purpose of this step, because the difference in position was not then sufficient to bring the thread in front of the needle 3. Also, the vertical position of the thread 5 on the transfer point 6 was not always certain. Hence this step could not be depended upon to work accurately.

60 According to the present invention, a very different step is provided for bringing the thread 5 in front of the needle 3. This step requires no special movement of the needle bar, and is positive and certain in its action. This step is accomplished by a special auxiliary needle 7 having a beveled or sword shaped point, which engages the thread 5 lying on the knocking over bits 8, pushes it in front of the needle 3, and positively 65 holds the thread 5 in this position.

With this new step, the manufacture of the

stocking proceeds up to the point illustrated by Fig. 3. Then the thread 5 is transferred to the needle 4 by the transfer point 6 as shown in Figure 4. As soon as this thread has been transferred, while the thread 5 extending from the needle 2 to the transfer point 6 is lying on the knocking over bits 8, the beveled edge of the auxiliary needle 7 pushes this thread in front of the needle 3 while all of the knitting needles are moving upward.

85 While the auxiliary needles 7 may be mounted and operated in various ways, it is of advantage to mount these auxiliary needles on the lace bar or transfer bar 9, so as to avoid additional operating mechanism. As the bar 9 has a pre-determined movement, the needles 7 are shaped to conform to this movement. They are so located, and are of such length that at the lowest position of the bar 9, the auxiliary needles 7 90 extend in proximity to the knitting machine 9p needles. The sword shape permits these auxiliary needles to enter between the knocking over bits 8, and push the thread to the desired position with a sort of cam action of the beveled 100 edge.

An improved and preferred modification of the 105 needle 7 is shown in Figures 8, 9 and 10. In this form, the shank of the auxiliary needle 7a is longer, and the point is provided with a groove 10 10 10. The point 11 of this form is also beveled laterally, to facilitate the entry thereof between the knocking over bits.

This arrangement permits the auxiliary needle, in the lowest position of the lace or narrowing 110 bar 9, to extend down over the machine needle 3, the point of which enters the groove 10. Thus the front faces of the auxiliary needle and the machine needle form a smooth edge or straight surface along which the thread 5 slides as these 115 needles rise together. Hence there is no possibility of the thread 5 sliding back along the beveled or sword shaped point and over the head of the needle 3, and thus escaping therebetween 120 to the rear of the needle 3.

The invention is not limited to the exact details disclosed, but instead embraces such embodiments of the disclosed idea as fall within the scope of the appended claims.

125 I claim:

1. In the manufacture of lace fabric on a flat knitting machine, the method of closing the opening formed by transferring loops outwardly from a plurality of adjacent needles, which comprises moving the thread which has not been formed into a loop, to a position in front of one but behind another of said empty needles, while maintaining said needles in alignment.

2. In the manufacture of lace fabric on a flat 135 knitting machine, the method of closing the opening formed by transferring loops outwardly from a plurality of adjacent needles, which comprises laying another course in which the thread adjacent the empty needles is not formed into loops, but lies loose behind said empty needles, transferring a portion of loose thread outwardly to an adjacent needle, and moving another portion of said loose thread to a position in front of the nearer empty needle, while maintaining said needles in alignment.

3. In a flat knitting machine adapted for the manufacture of lace fabric, mechanism for closing the opening formed by transferring loops outwardly from a plurality of adjacent needles, comprising an auxiliary needle adapted to move 140 145 150

the thread which has not been formed into a loop to a position in front of one of said needles while maintaining said needles in alignment.

4. In a flat knitting machine adapted for the manufacture of lace fabric, mechanism for completing the outline of the opening formed by transferring loops outwardly from a plurality of needles, comprising means for moving the thread which has not been formed into a loop to a position in front of one of said needles, said means comprising an auxiliary needle carried by the transfer bar and having a beveled lower edge adapted to cam said thread to said position while said needle remains rigid.

5. In a flat knitting machine having a transfer bar adapted for the manufacture of lace fabric, mechanism for completing the opening formed by transferring loops outwardly from adjacent needles, which comprises an auxiliary needle carried by said transfer bar and having a beveled lower edge adapted to push the thread which has not been formed into a loop forward in front of one of said empty needles, said auxiliary needle

having a groove adapted to receive the head of said empty needle and maintain it in alignment with the other needles.

6. In a flat knitting machine adapted for the manufacture of lace fabric, and provided with transfer points adapted to form an opening by transferring loops outwardly from a plurality of adjacent needles, in combination with mechanism for discontinuing the opening, including an auxiliary needle carried by the transfer bar and having a beveled lower edge adapted to engage the thread which has not been formed into a loop and which is lying on the knocking over bits, and move the thread to a position in front of one of the machine needles, said auxiliary needle having a groove adapted to cooperate with a machine needle, the front faces of the auxiliary needle and the machine needle forming a smooth surface which slides along the thread as both needles move upwards, and prevents the thread from falling behind the machine needle.
